(No Model.)

H. KAUFMANN.

LOUNGE.

No. 412,510.

Patented Oct. 8, 1889.

UNITED STATES PATENT OFFICE.

HERMANN KAUFMANN, OF MILWAUKEE, WISCONSIN.

LOUNGE.

SPECIFICATION forming part of Letters Patent No. 412,510, dated October 8, 1889.

Application filed January 26, 1889. Serial No. 297,605. (No model.)

To all whom it may concern:

Be it known that I, HERMANN KAUFMANN, of Milwaukee, in the county of Milwaukee, and in the State of Wisconsin, have invented 5 certain new and useful Improvements in Lounges and Analogous Furniture; and I do hereby declare that the following is a full, clear, and exact description thereof.

My invention relates to lounges and analogous furniture; and it consists in certain peculiarities of construction and combination of parts, to be hereinafter described with reference to the accompanying drawings and subsequently claimed.

15 In the drawings, Figure 1 represents a vertical longitudinal section of a lounge constructed according to my invention; Fig. 2, a vertical transverse section of the same taken on line 2 2 of the preceding figure; Fig. 3, a 20 detail transverse section with parts broken away; Fig. 4, a detail view of a crank that forms part of my invention; Fig. 5, a detail section on line 5 5 of Fig. 3, the crank being omitted.

25 Referring by letter to the drawings, A represents the side pieces, and B C the upholstered head and body portion of an ordinary lounge. Secured to transverse braces D E, that connect the side pieces A of the lounge, 30 are tapes F, the latter being interwoven by tapes G, that have their ends secured to said side pieces, these tapes serving as a support, for the purpose to be hereinafter described. Journaled to the side pieces A at opposite 35 ends of the lounge are rollers H, and similarly connected to the inclined portions A' of said side pieces is a spindle I, the latter being hollow for at least a portion of its length, and having a radial extension I', that is also hollow for at least a portion of its length. The spindle I is also provided with eyes J, to which are secured cords or tapes K, that connect with one end of a blanket L or other covering, as best illustrated in Fig. 1.

45 As best illustrated by Fig. 4, I unite two cylindrical sections M M' by means of a plate N, pivotally connected at its ends to said sections, the one M of the latter being provided with a radial lug O, this construction forming 50 a jointed crank that is fitted to slide within the hollow spindle I, the lug O on the crank being designed to fit the radial extension I'

of said spindle. When not in use, the jointed crank is straightened out and pushed back within the hollow spindle I, as best illustrated 55 in Fig. 3, the exposed end of said crank being preferably an ornamental knob. The blanket L or other covering is drawn out at the foot end of the lounge and wound back by means of the crank and spindle. The foot 60 end of the lounge is provided with a door P, that conceals the blanket L or other covering from view when drawn back out of the way, the rollers H facilitating the latter operation, and if there is any slack in the cords or tapes 65 K said covering will be supported on the tapes F G, although it is obvious that any other suitable support may be as readily employed.

Although I have shown and more particularly described my invention in connection 70 with a lounge, it is obvious that the said invention may be as readily applied to chairs, car-seats, and various other devices analogous to said lounge.

By the construction above described it will 75 be seen that any desirable amount of covering may be connected to a lounge or analogous piece of furniture so as to be readily drawn back and concealed beneath the same when not in use and as readily drawn out over 80 the occupant of the furniture any time such covering is found desirable.

Having thus fully described my invention, what I claim as new, and desire to secure by 85 Letters Patent, is—

1. The combination of a lounge or analogous piece of furniture, a spindle journaled in the frame of the device, a blanket or analogous covering normally supported beneath the furniture, and flexible connections uniting the spindle and covering, whereby the latter may be drawn out by hand and returned to its normal position by rotation of said spindle, substantially as set forth.

2. The combination of a lounge or analogous piece of furniture, a hollow spindle journaled in the frame of the device, a blanket or analogous covering normally supported beneath the furniture, flexible connections uniting the spindle and covering, and a jointed 90 crank telescopically arranged with relation to said hollow spindle, substantially as set forth.

3. The combination, with a lounge or analogous piece of furniture, of a hollow spindle

journaled in the frame of the device and provided with a radial extension, a blanket or analogous covering flexibly connected to the spindle, and a jointed crank loosely arranged in said spindle and provided with a lug that engages the radial extension thereof, substantially as set forth.

4. The combination, with a lounge or analogous piece of furniture, of a spindle journaled in the frame of the device, a blanket or analogous covering flexibly connected to the spindle, and rollers journaled in said lounge to facilitate the movement of the covering, substantially as set forth.

15 5. The combination of a lounge or analogous piece of furniture, a series of tapes secured to the frame of the device, a spindle journaled in said frame, a blanket or analogous

covering normally supported on the tapes, and flexible connections uniting the 20 spindle and covering, substantially as set forth.

6. The combination, with a lounge or analogous piece of furniture, of a spindle journaled in the frame of the device, a blanket or 25 analogous covering flexibly connected to the spindle, and a door connected to the foot end of said frame, substantially as set forth.

In testimony that I claim the foregoing I have hereunto set my hand, at Milwaukee, in 30 the county of Milwaukee and State of Wisconsin, in the presence of two witnesses.

HERMANN KAUFMANN.

Witnesses:

N. E. OLIPHANT,
WILLIAM KLUG.
